CLAIM

The ornamental design for a wet tool enclosure, as shown and described.

DESCRIPTION

FIG. 1 is a front perspective view of a wet tool enclosure comprising the new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof; and,

FIG. 7 is a top view thereof.

The broken lines are for illustrative purposes and form no part of the claimed design.
